UNITED STATES PATENT OFFICE.

STEWART H. MOORE, OF CHICAGO, ILLINOIS.

VALVE.

SPECIFICATION forming part of Letters Patent No. 739,334, dated September 22, 1903.

Application filed May 13, 1903. Serial No. 156,864. (No model.)

To all whom it may concern:

Be it known that I, STEWART H. MOORE, a citizen of the United States, residing at Chicago, in the county of Cook and State of Illinois, have invented a certain new and useful Improvement in Valves, of which the following is a specification.

My invention relates to an improved article of manufacture adapted to be used for valves, valve-disks, and the like, and has for its object to provide a new and improved device of this description.

My invention is illustrated in the accompanying drawings, wherein—

15 Figure 1 is a view of a pump with parts broken away, showing my improved valve in position. Fig. 2 is a view of one of the valves. Fig. 3 is an enlarged section therethrough. Fig. 4 is a view showing one way of combining the pieces of the outer covering for the valve. Fig. 5 is a view showing a modified method of connecting the parts of the covering. Fig. 6 is a view of the valve-disk embodying my invention.

25 Like letters refer to like parts throughout the several figures.

In the use of valves in pumps and the like, for example, it is desirable to have a valve which will be durable and which will adapt 30 itself to the seat in connection with which it is used and which will also remain unaffected by the fluid or material passing through the pump, and this is particularly true when this fluid is hot or is some other fluid than

35 water.

Referring now to the drawings, I have shown a valve A in Figs. 1, 2, and 3 adapted to be used in pumps for pumping any desired material. This valve consists of an inner elastic 40 part A', which may be rubber or any other suitable elastic substance. This elastic inner portion is covered by a light homogeneous sheet metal—such, for example, as copper—which forms a complete covering. This covering may be constructed and assembled in any desired manner—as shown, for example, in Fig. 3. The valve is provided with a central opening A², and the covering is formed in two pieces A³, A⁴, each provided with projecting flanges A⁵, which are preferably bevelled, as shown, so as to fit together. The two

parts of the covering are placed about the inner elastic portion and are held in position in any desired manner, as by brazing together. This method completely incases the elastic 55 material and seals it within the covering, so that it is protected from the fluid with which the device comes into contact. The construction of the lapping over of the parts A⁵ is illustrated on an enlarged scale in Fig. 4. It is of 60 course evident that the parts of the covering of the device may be connected together in any desired manner, and I do not limit myself to such connection. I have shown, for example, in Fig. 5 a different connection where the edges 65 of the parts of the covering are lapped over and the joint thus made, and this joint may be soldered or brazed or otherwise treated. In Fig. 6 I have shown a valve-disk constructed in the same manner and adapted to be used 70 wherever applicable. With this construction it will be seen that a device is produced which is elastic and which yet has the characteristics of a metal valve and that when this valve is used it accommodates or adapts 75 itself to the seat or surface in connection with which it is used, because of the yielding surface of the device itself, and that it thus produces a tight joint. This device is also noiseless when used in pumps as a valve, for example, or as an elastic liner between heavy 80 bearings and does away with hammering, jar, and the like. This valve may also be used in pumps, for example, that are used to pump hot liquids or acids or corroding gases 85 or oil or any other material which has a tendency to attack the valve and when so used is free from attack and has the beneficial qualities hereinbefore described.

I have described in detail a particular construction embodying my invention; but it is of course evident that this construction may be varied and changed as to the details without departing from the spirit of my invention. For example, the manner in which the 95 pieces of the covering are connected together may be varied, and the number of pieces into which the covering is divided and the particular form or shape may be altered.

When the device is used, for example, as a 100 liner for heavy bearings, it will of course take the shape required for this use.

I have not designated all the uses to which the device may be applied, as such uses will readily occur to those versed in the art.

I claim—

- 5 1. A valve consisting of an inner elastic portion with an outer protecting metallic covering completely inclosing said elastic portion and sealed to protect the elastic portion from the fluid.
- 10 2. An article of manufacture comprising an inner elastic portion, an outer sheet - metal covering consisting of parts connected together at their meeting edges so as to completely inclose the said elastic material.
- 15 3. A valve device consisting of a unitary flat disk made up of a sheet-metal outer covering and an inner elastic portion confined within said covering and protected thereby.

4. A valve device comprising a disk of elastic material, a sheet-metal covering therefor comprising two or more portions provided with engaging parts fastened together so as to form a unitary construction.

5. An article of manufacture comprising an inner, elastic portion having an opening there- 25 through, an outer sheet-metal covering consisting of two parts connected together and provided with laterally - projecting parts which extend into said opening and along the outer edge of the elastic portion, said projecting parts meeting and sealed so that the elastic portion is completely inclosed.

STEWART H. MOORE.
